GARMENT DISPLAY FORM

Irene P. Smith, Needham, Mass., assignor to The
William Carter Company, Needham Heights,
Mass., a corporation of Massachusetts

Application June 6, 1950, Serial No. 166,337

3 Claims. (Cl. 223—68)

1

This invention relates to a display form particularly useful in the merchandising display of garments. It has for an object the provision of an attractive form wherein certain of the elements thereof are detachable to facilitate the positioning of apparel thereon for display purposes. The objects of the invention will be more fully apparent when considered in connection with the following description of a typical embodiment of the invention as illustrated in the accompanying drawings wherein:

Fig. 1 is a front elevational view of the display form, with portions thereof broken away to clarify inner structure;

Fig. 2 is a vertical cross-sectional view thereof taken along the line 2—2 of Fig. 1;

Fig. 3 is a horizontal cross-sectional view taken along the line 3—3 of Fig. 1; and

Fig. 4 is an enlarged detailed cross-sectional view taken along the line 4—4 of Fig. 1.

In the embodiment shown in the drawing, the parts intended to be exposed are fashioned from relatively stiff, plastic sheet material presenting edge outlines simulating the corresponding portions of a human figure. Thus, for the display of body-covering garments such as shirts, dresses, nightgowns, etc., the figure shown in the drawing has a head- and neck-forming element, and arm- and leg-forming elements molded or cut from sheets of such plastic material. Desirably, the material is transparent, for example, transparent polystyrene, so that the outline edges thereof catch the light and accentuate the outline appearance of the form.

In the drawings, the transparent material thus comprises four pieces, a head- and neck-forming element 10, arms 12 and 14, and leg portion 16. The remaining parts include a torso 20 and base frame or standard 22.

The torso 20 is adapted to receive and hold the head-, arm- and leg-forming elements and while it may be made of the same transparent plastic material, it is more economical to fabricate it from less expensive material, for example, wood, since it is intended to be covered by the garment to be displayed. The top portion of the torso has a cut-out in the form of a semi-circular recess 24 for a purpose to be later described.

In any event, the torso 20, as appears in Fig. 2, has a thickness greater than the thickness of the sheet material of elements 10, 12, 14 and 16 and may conveniently comprise plywood. For the purposes of holding the other elements, it is provided, as hereinafter described, along its edges with suitable recesses for receiving extensions of

the outline transparent sheet material. The upper edge of the torso 20 is provided with a slot-like recess 25 which receives an extending portion 26 of the head-forming element 10. Similarly, the side edges of the torso 20 are provided adjacent the upper ends with recesses 28 for receiving extensions 30 of the arm-forming elements 12 and 14. Lastly, the bottom edge of the torso is provided centrally thereof with an upwardly extending slot-like recess 32 for receiving an upwardly extending extension 34 of the leg-forming element 16. Where plywood is used, these recesses may be provided most conveniently by fabricating the torso from three laminations of plywood, the middle lamination 36 having a top edge terminating at the line 38 in Fig. 1 and having the outline of recess 32 cut in its bottom portion. Affixed to this central portion 36 on either side thereof is another layer of plywood having the full outline of the torso 20. In this manner, both the head-forming element recess 25 and the arm recesses 28 are simultaneously formed during the fabrication of the torso 20, but, in order to maintain the upper outer laminations of the torso properly separated, blocks 40 of the same thickness as the middle lamination 36, are interposed therebetween as shown in Fig. 1, and thus serve also to define side limits of the head-forming element recess 25. The recesses 28 are therefore open along the top edge of the torso 20 inwardly as far as blocks 40, as well as along the side edges. The leg-forming element 16, torso 20 and head-forming element 10 are thus joined with mortise-joints.

Since the arm-forming elements 12 and 14 extend downwardly, it is necessary to provide some further retaining means for them and these means take the form of pegs 42 extending transversely across the recesses 28 and positioned to engage slots 44 provided as shown in the arm extensions 30. These pegs and slots, in cooperation with the abutting engagement of the lower inner edges 48 of the arm-forming elements 12 and 14 with the edge of the torso 20 proper, serve to hold the arms firmly but detachably in place since they may be lifted upwardly and outwardly to free them from engagement with the pegs 42.

The standard 22 is also slotted at 50 to receive the feet of leg-forming element 16. This slot 50 is angled as more clearly shown in Fig. 3 so that the feet fit into the slot at a slight angle to each other to tension the sheet material of the one-piece bifurcated leg-forming element 16 out of its normal plane in order to give the structure more rigidity.

3

The separability of the elements facilitates shipment in knock-down form and also the placing of garments, for example, baby garments thereon, since the head-forming element 10 may be inserted through the neck of the garment after the garment has been positioned over the torso 20, the extension 26 being of less width than the maximum width of the head and therefore can be more readily inserted through the neck of the garment, than the neck of the garment may be passed over the head. Likewise, the arms may be inserted through the armholes or sleeves after the garment has been placed over the torso, thus avoiding stretching the garment, as would be necessary if the arms were not detachable. Thus placed, garments, such as shirts, night-gowns and dresses will conceal the wood torso-forming element 20.

One should note that because of the manner of joining the various elements, there are no protruding fastenings or joints which might become misaligned and, therefore, there is nothing to catch a garment as it is placed over the torso or legs or to hamper the free and straight hanging of the garment on the form being displayed.

A desirable advantage of the provision of the top semi-circular cut-out 24 in the torso 20 is that hanger labels, conventionally provided on the inner side of the back neck portion of a garment, are visible through the transparent head-forming element extension 26 and thus display the trade mark, maker's name, model number, size or whatever else appears on the label, to the viewing public.

While the embodiment shown in the drawings includes many advantageous features as above described, it will be understood that certain of the individual features may be utilized in the absence of other of the features while still appropriating the invention.

I claim:

1. A display form for garments comprising head-, arm- and bifurcated leg-forming elements of substantially flat, relatively stiff transparent sheet material having outlines along their edge portions simulating the head, arms and legs, respectively, of a human figure, and a flat torso of slightly greater thickness than the thickness of said sheet material adapted to support said head- and arm-forming elements and to be supported by said leg-forming elements, said torso having along its top, side and bottom edge portions slot-like recesses for detachably receiving extending portions of said elements to form mortise-joints therewith, and rigid pegs extending transversely of the arm-forming element receiving recesses, said arm-forming ele-

ments having slots for engaging said pegs and edge surfaces cooperating with edge surfaces of said torso to limit downward movement of said arm-forming elements relative to said torso, and a standard for said form having slots therein for receiving the bottom edge portions of said leg-forming elements, said slots being angularly related for tensioning the sheet material of said leg-forming element out of its normal plane when said leg-forming element edge portions are seated in said standard slots.

2. A display form for garments comprising head- and arm-forming elements of substantially flat, relatively stiff sheet material having outlines along their edge portions simulating the head and arms respectively of a human figure, and a torso adapted to support said head and arm-forming elements, said torso having slot-like recesses along its side edge portions for detachably receiving extending portions of said arm-forming elements to form mortise-joints therewith, and rigid pegs extending transversely of the arm-forming element receiving recesses, said arm-forming element extending portions having slots extending upwardly from bottom edge portions thereof for engaging said pegs for detachably attaching said arm-forming elements to said torso, and edge surfaces on said arm-forming elements cooperating with edge surfaces of said torso to limit downward movement of said arm-forming elements relative to said torso.

3. A display form for garments comprising a bifurcated leg-forming element of substantially flat, relatively stiff sheet material and torso-, arm- and head-forming elements, said torso-forming element having a slot-like recess along its bottom edge portion for detachably receiving an upwardly extending portion of said leg-forming element, and a standard for said form having slots therein for receiving bottom edge portions of said leg-forming element, said slots being angularly related, the bottom edge portions of said leg-forming element being positioned in said slots with the sheet material of the leg-forming element tensioned out of its normal plane to support said form in upright position.
